UNITED STATES PATENT OFFICE.

FRANK W. McLEAN, OF MORENCI, ARIZONA.

AUTOMATIC COUNTING AND RECORDING MECHANISM.

1,104,307.

Specification of Letters Patent. Patented July 21, 1914.

Application filed March 18, 1913. Serial No. 755,265.

To all whom it may concern:

Be it known that I, FRANK W. McLEAN, citizen of the United States, residing at Morenci, in the county of Greenlee and 5 State of Arizona, have invented certain new and useful Improvements in Automatic Counting and Recording Mechanisms, of which the following is a specification.

My invention relates to counting and registering mechanism and particularly to mechanism designed for the purpose of registering the passage of a car moving either in a vertical or a horizontal direction.

The primary object of my invention is 15 the provision of a mechanism for the purpose of registering the passage of the skip or cage in a mine shaft, and a further object in this connection is to provide mechanism registering the movements of the skip or 20 cage with relation to the time during which the cage or car is moving upward and the time that the cage or car is at rest.

A further object of the invention is to 25 provide means for according and thereby counting the number of trips made by a skip, cage or elevator car and in this connection to provide means for registering in a distinct manner every tenth trip of the 30 car or cage so that the total number of trips made by the car between certain hours may be easily calculated.

A further object of the invention is to provide in connection with mechanism for recording the number of trips made by a cage 35 or car within a certain definite period, a mechanism recording the distance traversed by the car to various levels, the time of said trips and the periods of time during which the car or cage lay idle.

40 A further object is to provide means whereby the trip registering mechanism may be used for the purpose of registering the number of cars passing a certain point.

A still further object is to provide in a 45 mechanism of the character described, a cylinder adapted to receive thereon a recording strip upon which the record of the number of trips made by a car or cage may be registered, provide a vertically movable stylus 50 operating over said strip, provide means actuated by the movement of the car for causing a corresponding movement of the stylus, and means actuated by a movement of the stylus for rotating the recording cylinder a 55 certain amount after or before each trip of the car.

A further object in this connection is to provide an auxiliary stylus adapted to perform its function on every tenth trip of the car which will indicate upon a recording strip said tenth trip thereby to permit the total number of trips to be very easily calculated.

Other objects will appear in the course of the following description.

My invention is illustrated in the accompanying drawings, wherein:

Figure 1 is an elevation of the upper end of the hoisting mechanism of a mining cage or like elevator with my recording mechanism applied in conjunction therewith; Fig. 2 is a perspective view of the recording mechanism forming the subject matter of my invention; Fig. 3 is a side elevation of the recording mechanism looking toward the side 75 of the mechanism opposite to that illustrated in Fig. 1; Fig. 4 is a top plan view of the mechanism illustrated in Fig. 3; Fig. 5 is an end elevation of the mechanism illustrated in Fig. 3; Fig. 6 is a fragmentary detail sectional view on the line 6—6 of Fig. 5; Fig. 7 is a fragmentary detail elevation of one end of the stylus carrier broken away to show the means for yieldingly forcing out the lower stylus; Fig. 8 is a detail elevation 80 of a portion of a recording sheet showing the record made thereon; Fig. 9 is a detail perspective view of the member 78 looking from the inside to show the pawl in place thereon; Fig. 10 is a side elevation of the 90 cam bar used in connection with the mechanism shown in Fig. 11; Fig. 11 is a perspective view of one of the rails of the track showing my mechanism as applied thereto 95 for recording the passage of cars along the track.

Referring now to Fig. 1, A designates the winding drum of a hoisting mechanism of any suitable character such as ordinarily used in mines. Operatively connected to 100 the shaft 3 of this winding drum by means of a sprocket chain 4 is a shaft 5 carrying thereon a worm 6 which engages with a pinion or worm wheel 7 mounted on a shaft 8, this shaft in turn carrying a pinion 9 105 which meshes with a gear wheel 10 upon the shaft 11 on which there is mounted a pointer 12 moving over a dial 13. All these parts are of any usual or approved construction and form no part of the subject matter of 110 my invention, the mechanism being designed merely for the purpose of driving the shaft

11 at a reduced speed but at a proper ratio to the shaft 3, so that as the cable *a* on the winding drum A winds up or unwinds, the pointer 12 will indicate the various levels or floors to which the elevator, car, skip or cage has arrived. Mounted upon the shaft 11 is a gear wheel 14 which meshes with a rack bar 15 which in turn is connected in any suitable manner to a link 16 which at its lower end is connected to a lifting rod 17.

10 Referring now to Figs. 2, 3, 4 and 5, it will be seen that the lifting rod 17 passes down between a pair of parallel vertical posts 18, these posts being mounted at their lower ends in a plate 19 which in turn is supported on posts 20 disposed at the four corners of the plate 19 extending downward and engaging with a base plate 21 of any suitable construction. The post 20 is surrounded by sleeves 22* spacing the plate 19 from the base plate 21. The posts 18 at their upper ends pass through the horizontal arm 22 of an angular member 23 whose function will be later described. The upper ends of 25 the post are threaded for engagement by nuts 24 and the member 22 is clamped down upon the upper ends of the posts 18 by means of these nuts 24 and is held rigidly in position. The member 22 is perforated at 30 25 for the passage of the actuating rod 17.

35 Rotatably mounted upon the base plate 21 is a ratchet wheel 26 which may be of any suitable construction, and mounted upon the shaft of the ratchet wheel and disposed upon the plate 19 is a gear wheel 27. Rotatably mounted upon the plate 19 is a cylinder 28 adapted to support thereon a recording sheet, as will be later stated. The base of this cylinder is provided with 40 gear teeth 29 which mesh with the teeth of the gear wheel 27 so that as the ratchet wheel 26 is rotated the gear wheel 27 rotates the cylinder 28. It will be obvious that the motion of the ratchet wheel 26 is 45 very much reduced before it is transmitted to the drum 28 so that a very slight movement of the cylinder 28 will correspond to a one-step movement of the ratchet wheel 26.

50 The recording sheet 30 is supported in place upon the cylinder 28 by means of the upper and lower bands 31 and 32, both of these bands being constructed in the same manner and held in place by like mechanism. The cylinder 28 is hollow, and extending 55 across the cylinder 28 are the upper and lower resilient rods 33 corresponding one to each band. These rods are attached firmly to the inside face of the cylinder 28, as at 34, and at their other ends project through the 60 elongated apertures 35 formed in the wall of the cylinder 28. The extremities of the rods are annularly notched as at 36. At one end of each of the apertures 35 there is disposed a clamp 37 which engages one end of 65 the corresponding band and which is pro-

vided with a tooth 37* engaging the slot 35. The opposite end of the band 31 is formed with a perforation 38 through which the notched extremity of the rod 32 is adapted to pass. The rods 33 being resilient will act 70 to draw the free end of each band 31 toward the fixed end thereof in position to clamp the sheet 30 between the bands of the cylinder. When, however, it is desired to release the sheet 30 it is only necessary to retract 75 the rods 33 which will loosen the bands, whereupon the bands will be released and the clamp 37 will spring outward from the slot 35 permitting the sheet to be readily removed and replaced.

80 Mounted above the cylinder 28, in approximately axial alignment therewith, is a casing 39 containing spring-actuated clock mechanism or any other suitable motor designated 40. This clock mechanism has a winding key 41 whereby the spring of the clock mechanism may be wound up and an arbor 42 which extends up through the casing and which is connected to a rotatable plate 43 having a downwardly extending flange 44. The plate 43 has a rim 45 which extends over the flange 44 and is adapted to engage the upper edge of a recording sheet 46. This strip or sheet 46 is held in place by any suitable means, but as shown for the 90 purpose, the rim 44 has been provided with two downwardly extending resilient fingers 47 which grip the overlapped ends of the strip 46. The casing 39 is shown as supported by means of a bracket 48 which extends downward and is mounted upon the plate 19.

95 Supported upon the rods 18 as previously described is a member 23 angular in form so as to provide a transversely extending bar 105 22 and a laterally extending plate 49. The rod 17 passes through the transversely extending bar 22 and its lower end is connected to a slide or cross-head 50 formed with openings 51 for the passage of the rods 18, 110 which openings permit the sliding member 50 to shift up and down on and be guided by the rods 18. Projecting from the end of the slide 50 which is adjacent the cylinder 28 is a stylus 52 which has an upwardly inclined extremity bifurcated to accommodate a thin-edged roller or wheel 53 which forms the stylus proper of the device. The slide 50 therefore constitutes a stylus carrier. The stylus 53 makes the record upon 115 its recording sheet by superposing upon the record sheet a carbon sheet so that as the wheel 53 moves over the carbon sheet a mark will be left upon the recording sheet beneath. Inasmuch as the rod 17 moves up 120 and down with each up and down movement of the elevator car, and as its distance of travel has a definite ratio with the elevator, cage or skip, it is obvious that the mark made upon the record sheet 30 will indicate 125 130

the travel of the elevator. As will be apparent later on, only one vertical mark is made upon the recording sheet for each round trip of the skip or car.

- 5 Inasmuch as the rod 17 is the actuating rod and operatively connected to the car, it is obvious that some means must be provided for transmitting the movement of the rod 17 to the ratchet wheel 26 whereby 10 the recording cylinder is shifted, it being of course necessary to shift the recording cylinder one step for each up and down movement of the skip, cage or car. For the purpose of securing this step by step 15 movement of the cylinder 28 I provide the following mechanism. Mounted in guides 54 just below the plate 19 is a reciprocatable pawl carrier designated 55, see Fig. 6. One end of this pawl carrier is reduced and 20 passes through an opening in one of the guides 54, while the opposite end is reduced as at 56 and surrounded by a coil spring 57 which bears against the corresponding guide 54 so that the spring will retract the pawl carrier after each actuation. Mounted 25 upon the pawl carrier is a pawl 58, see Fig. 6, which is forced against the ratchet teeth of the wheel 26 by means of a spring 59. The movement of the pawl away from the 30 wheel 26 is limited by means of a stop screw 60. It will be obvious now that when the pawl carrier is shifted to the right, in Fig. 6, that the pawl 58 will engage with the teeth on the wheel 26 and will cause a forward movement of this wheel, and that 35 upon a backward movement of the pawl carrier the pawl will escape past the tooth it was previously in engagement with and slip into the tooth just behind. The forward movement of the pawl carrier 55 and 40 hence the amount of rotation given to the wheel 26 is limited by a pivoted stop pawl 61. This stop pawl 61 is pivoted intermediate its ends as at 62 in a supporting member 63 bolted to the base plate 21. The forward or tooth-engaging end of this pawl is adapted to engage with the teeth of the wheel 26 and prevent any backward movement of the wheel 26. The rear end of this 45 pawl 61 is vertically widened, and passing through the rear end of the pawl is a stop screw 64 which is disposed in alignment with the reduced end 56 of the pawl carrier 55. As the pawl carrier moves forward it is 50 obvious that the active end of pawl 61 will be moved outward against the force of a spring 65 and the outer end of the pawl will move toward the reduced end 56 of the pawl carrier. The end of the stop screw 64 and 55 the end of the reduced portion 56 of the pawl carrier meet at the moment when the pawl carrier and its pawl have moved the wheel 26 forward one notch. At this point 60 the pawl carrier is allowed to slip backward, as will be later described, and the pawl

moves back one notch. As soon as the tooth has passed the active end of the pawl 61, the spring 65 will force the pawl back into engagement with the teeth. Below the pawl 61 is mounted a second pawl 66 which is 70 forced into engagement with the teeth 26 by means of a spring 67. This pawl 66 acts upon the tooth in advance of the tooth acted upon by the pawl 61. It will thus be seen that upon each reciprocation of the sliding pawl carrier 65, the wheel 26 will be moved forward one step or notch, and the wheel 26 will cause the moving forward of the cylinder 28 a certain relatively small distance. Thus with each reciprocation of the rod 17 the slide 50 will be reciprocated and before such reciprocation has been accomplished the cylinder will have moved forward to bring a fresh portion of the record sheet in front of the stylus 53.

85 The means for accomplishing the reciprocation of the pawl carrying bar 55 is as follows. The outer end of the slide 50 is laterally enlarged, as at 68, see Figs. 2 and 4, and resting against the face of this enlarged portion 68 is a flat bar 69 which bar extends downward and at its lower end is widened and provided with the outwardly projecting lug 70 the upper end of which is rounded or beveled. Resting against the face of this bar 69 is a flat bar 71 which at its upper end extends over the upper end of the bar 69, as at 72, see Fig. 2, and at its lower end is thickened so as to extend under the lower end of the bar 69, as at 73, and is extended 90 downward and then widened as at 74, this widened portion 74 being connected to the relatively narrow rod 71 by means of an inclined face 75 forming a cam which engages with a roller 76 carried in a longitudinal 105 slot 77 formed in the pawl carrier 55. It will be seen now that upon each vertical movement of the rod 71 the inclined face 75 will come in contact with the roller 76 and will force the pawl carrier 55 laterally 110 and cause the pawl to advance the wheel 26 one step. This advancing action of the rod 71 is intended to occur only on the initial movement of the slide 50 from any position in which it may be, and the downward movement of the rod 71 and the cam 74 will occur upon the initial downward movement of the slide 50. The reason for this is that the rod 17 and the slide 50 will raise or 115 lower a distance depending upon the amount of vertical movement of the cage or car. This distance will vary as the car falls or rises a greater or less distance, but the distance traversed by the wheel 26 upon each reciprocation either partially or fully of the rod 17 will be the same under all circumstances, as it is only necessary to advance the recording cylinder 28 one step upon either a partial or a full reciprocation 120 of the rod 17.

In order to secure a single forward step of the wheel 26 on each partial or full reciprocation of the rod 17, I have provided for a sliding engagement between the end face of the slide 50 and the rods 69 and 71. In order to hold these rods in engagement with the face of the slide 50 I provide a bridge piece designated 78 which is formed as illustrated in Fig. 9. This piece extends 5 transversely across the face of the head 68 and is so formed as to provide two inwardly extending terminal portions 79 and 80 which bear against the face of the head 68 and which are perforated for the passage of bolts 81 which hold the bridge piece in place. The body of the bridge piece extends downward, as at 82, so as to bear against the face of the rod 71 and is also provided with a lateral flange 83 defining 15 a space or chamber 84 within which is pivotally mounted the pawl 85. This pawl 85 has a tooth 86, and on the inner face of the tooth is a rounded portion 87. The tooth has a thickness equal to the thickness of 20 the toothed ratchet bar, but the rounded portion bears against the face of the bar 69, as illustrated in Fig. 2. The pawl is forced with its tooth into engagement with the ratchet teeth on the bar 71, by means of a 25 spring 88 mounted within the chamber 84. Above the bridge piece 78 and resting thereon is a friction block 89 which is attached to the upper end of a spring 90 which extends down and at its lower end is fastened 30 to the outer face of the body portion of the bridge piece. The face of this block 89, which is preferably of brass or like metal, is resiliently forced against the face of the rod 71 and not only frictionally engages this rod 35 but resiliently forces this rod and the rod 69 into frictional engagement with the face of the head 68. The lower end of the rod 69 is enlarged or widened and formed with the outwardly projecting lug 70, as previously 40 stated, this lug 70 projecting immediately behind the rear edge of the rod 71. The upper end of the rod 69 is also widened, as at 91, and formed with the outwardly 45 projecting rib or lug 92 which normally rests upon the upper edge face of the member 93 and which is also disposed behind the rod 71, as shown in Figs. 5 and 2.

Attached to the plate 49 by means of bolts is the bar 93 which is cut away to permit the passage of a cam bar 94. This bar 50 is held in place by means of a screw 95 which prevents any vertical movement of the bar. The lower end of the bar is angularly turned, as at 96, and passing through 55 this ear 96 is a bolt 97 which passes through a slot 98 in an angle plate 99 attached to the upper face of the plate 19. Thus the cam bar 94 is held rigidly in position, but it may be adjusted with relation to the rods 60 69 and 71. This cam bar is formed upon

its forward edge with an outwardly projecting lug 100 the lower edge of which is beveled as at 101. The upper end of the cam bar 94 is enlarged and the lower edge of this enlargement is beveled as at 102. The edge 101 coacts with the beveled edge 103 of the enlarged portion of the rod 69, and the beveled edge 102 coacts with the upper end of the lug 92.

When now the cross head or slide 50 rises 75 the tooth 86 will engage with one of the ratchet teeth on the bar 71 and the bar 71 together with the bar 69 will be lifted with the cross head 50 until such position is reached that the beveled edge 91 engages 80 with the beveled edge 101 on the cam bar 94, whereupon the bar 69, which is a pawl tripping device, will be shifted outward and engaging the rounded edge 87 of the pawl will force the pawl 86 out of engagement with 85 the tooth on rod 71. As a consequence the cross head will now rise without affecting the rod 71 or its companion rod 69. There is sufficient frictional engagement between the rods 71 and 69 and the cross head to permit 90 the rods 61 and 71 to travel upward with the cross head, were it not that the beveled edge 102 on the upper end of the cam rod 94 engages with the beveled flange 92 and stops the upward movement of the rods. Thereafter 95 the cross head 50 or slide travels upward by itself without carrying with it either the rod 69 or 71. Upon the initial downward movement of the cross head the frictional engagement between the rods 69 100 and 71 and the portion 68 will cause the rods 69 and 71 to move downward with the cross head until a position is reached where the lug 70 will engage with the upper face of the yoke 55. This will stop the descent of the 105 rods 69 and 71 and the cross head will continue its descent. It will be seen from this construction that the initial movement of the car, skip or cage from a definite starting point, as, for instance, the top of the shaft, 110 will cause a forward movement of the wheel 26 one step and that after this has been accomplished the cage will continue its downward movement to any position within the shaft without further affecting the wheel 23. The cage may stop at a certain level 115 and then continue its movement farther downward, but it will not again turn the wheel 23. The cage must come back to its initial position and again start out upon its travel before the wheel 26 will be stepped forward. Thus the wheel 23 will step forward only upon a complete journey of the cage or car from the point of starting which will include a movement of the car away 120 from the point of starting and back again to the starting point.

The mechanism is so arranged that only a relatively short movement of the car or cage from the starting point is necessary to move 125

the rod 71 a sufficient distance to actuate the pawl carrier 55 and step the wheel 23 one step. After that it does not matter how many times the elevator stops and starts, the wheel 26 will not be actuated until the car or cage has returned to the starting point and is again started. It will be seen also that if the car or cage runs the full length of the shaft the cross head or slide 50 will be raised a distance corresponding to the travel of the elevator to the point where it returns. If the car or cage goes the full distance of the shaft, a vertical line will be made upon the recording sheet on the cylinder 28 which will extend nearly the full width of the recording sheet. If, however, the car goes, say, half way down the shaft, stops at a level and returns, the line drawn upon the recording sheet will only be one-half the width of the record surface of the sheet, and the same applies of course if the elevator goes only a quarter the distance of the depth of the shaft. The line drawn upon the paper and indicating the movement of the elevator will always be proportionate to the full travel of the elevator so that the lines will indicate not only the number of movements that the elevator car or cage has made, but also whether the car on one trip traveled the full length of the shaft or only a portion of that length before returning to the starting point. Inasmuch as the movement of the cylinder 28 is very slight, the lines drawn upon the face of the recording sheet and indicating each a trip of the elevator will be very close together and therefore hard to count. For the purpose of providing indications marking every tenth trip of the car or cage, I provide the face of the wheel 26 with upwardly projecting lugs 104. These are arranged radially and disposed upon the peripheral margin of the wheel 26. Mounted upon one edge of the plate 19 and projecting over the exposed portion of the wheel 26 is a bracket 105 which is perforated at its outer end for the passage of a vertically disposed plunger 106. This plunger at its lower end carries a roller 107 which is adapted to be engaged by the lugs 104. The upper end of a plunger is formed with a head 108 which engages with the lever 109 pivoted between upwardly projecting ears 110 carried on the bracket 105. The inner end of this lever is reduced as at 111 and extends through a perforation formed in the outer end of an arm 112, this arm at its inner end being pivoted at 113 to a supporting rod 114. This supporting rod is vertically arranged and at its lower edge is supported in a recess or pocket 115.

The rod passes through an opening 116 in the slide 50 and at its upper end is rigidly attached to the strip 22, as plainly seen in Fig. 2. The arm 112 is angularly bent, and pivoted to this arm 112 just forward of its

pivotal point 113 is the lower end of a rod 117. The upper end of this rod is linked to the rod 114 by means of the pivot link 118, and connected to the upper end of the rod is the coil spring 119 which is attached at its upper end to the strip 22. The spring at its upper end acts to raise the rod 117 and hold it in this raised position. When, however, the roller 107 on the lower end of the plunger 106 strikes one of the beveled lugs 104, it will cause a depression of the inner end of the lever 109, which in turn will depress the arm 112 and the arm 117. Because of the fact that the rod 117 is arranged for parallel motion by being linked at its upper and lower ends to the fixed bar 114, it is obvious that when the rod 117 is depressed it will move downward and toward the extremity of the slide 50, that is, toward the stylus 53. Disposed in the slide 50 and below the stylus 53 is a sliding stylus shank 120 which at its outer end has the ears 121 in which is pivoted the stylus roller 122. The rear ends of this stylus shank abuts against the rod 117 so that when the rod 117 is depressed and moves toward the recording cylinder, it will act to force the sliding stylus shank outward and force the stylus 122 into engagement with the recording sheet. Inasmuch as the stylus 122 is below the stylus 53, it is obvious that it will merely continue the mark made by the stylus 53 below or toward the lower edge of the recording sheet. The slide 120 is slotted for the accommodation of a spring 123 which acts to return the slide 120 to its original position. As shown in Fig. 7, the ears 121 are pivoted within the stylus shank 120 and a spring acts to yieldingly force these ears outward. When the stylus 122 strikes the recording sheet, these pivoted ears will yield inward so that too much pressure will not be brought to bear against the recording sheet which will act to tear it.

The lugs 104 are preferably arranged coincidentally with every tenth tooth of the wheel 26 so that upon each tenth trip of the car or skip, one of the lugs 104 will engage with the plunger 106 and cause the projection of the stylus 122.

The record made upon the recording sheet is shown in Fig. 8, and it will be seen that this record consists of vertical lines *a* disposed relatively close together and that the height of these lines from a base *b* will indicate the extent of movement of the elevator from the top toward the bottom of the shaft. The base line *b* is supposed to be the top of the shaft, inasmuch as the downward movement of the elevator car causes the upward movement of the stylus. As will be seen from this record, and counting from the left hand end of the record, the car or skip made about four trips from the bottom of the shaft to a level half way the length

of the shaft. It then made about three trips from the top of the shaft to a point seven-eighths of the distance of the shaft and then made nine trips the full length of the shaft, 5 etc. It will be seen that with every tenth trip of the car or skip the auxiliary stylus 122 marked a line extending below the base *b*, this line being designated *c*. In Fig. 8, 10 lines are drawn relatively wide apart so as to be distinct, but in the actual record the lines are drawn so closely together that it is most convenient to have a means for indicating every tenth trip of the car or cage.

It is often necessary to provide means for 15 showing not only the number of trips made by an elevator within a certain length of time, but also showing the periods during which the elevator is at work and at rest so that the amount of work done by a hoisting 20 apparatus or elevator may be determined. It is for this purpose that I provide the time recording drum 43. Upon the exterior of this drum is fastened, as previously described, a strip of recording paper divided 25 by vertical lines indicating time divisions and horizontal lines indicating the different levels or stages of the mine or structure within which the elevator or cage is used. Such a trip is shown in Fig. 3, wherein the 30 vertical lines indicating time are designated *d* and the horizontal lines indicating the stages or levels of the mine or other structure are designated *e*. This strip is shown as marked off into hours and half-hours by 35 the vertical lines *d*, and the record is supposed to be begun at 7.30 a. m. at the right hand corner of the end of the strip. The record consists of a line drawn in ink. Where the elevator is at rest the line will be 40 horizontal and where the elevator is traveling the line is vertical.

A line extending from the base line indicates a trip of the elevator, car or skip from the surface downward into the shaft and 45 back again, and it is obvious that the character of this line will indicate the relative speed of the elevator, its delay at various levels, and in fact the history of each trip from the top of the shaft down into the 50 shaft and back again. The mechanism whereby this record is secured is as follows. Depending from the cross bar 22 and rigidly attached thereto is a strip 124. The 55 downwardly extending terminal portion of this strip carries a block 125 the side edges of which have undercut grooves cut in to it to form a guide. Pivotaly mounted upon the plate 19 is a lever 126 having two arms extending at an acute angle to each other. 60 One of the arms extends upward at an incline to the vertical and is longitudinally slotted as at 127. A pin 128 upon the slide or cross head 50 engages in the slot 127, and it is obvious that as the slide or cross head 65 rises the lever 126 will be moved from a po-

sition where the arm 126^a is inclined, to a position where this arm is approximately vertical, and the arm 126^b of the arm 126 will be raised under these circumstances, so that as the slide is raised the arm 126^b is raised and 70 as the slide is lowered the arm 126^b is lowered. Attached to the extremity of the arm 126 and extending upward therefrom is a connecting rod 129 which at its upper end is connected to a slide 130. This slide is bifurcated so as to provide parallel, upwardly extending members 131 having angular inner faces which engage in the dovetailed grooves formed in the outer side edges of the member 125. This slide carries attached to 80 it an upwardly projecting arm 132 preferably in the form of a light spring. This arm at its upper end carries a pen 133 so formed as to retain a sufficient quantity of writing fluid such as red ink. As the rod 17 rises, 85 carrying with it the slide or cross head 50 the slide 130 will also be raised carrying with it the pen 133, and this pen being in contact with the recording sheet, a mark will be made upon the recording sheet. As 90 the drum carrying the recording sheet is traveling forward under the impulse of the clock mechanism, it is obvious that a time record of the actuation of the car, skip or cage will be made. It is also obvious that if 95 the elevator, car or cage goes to the bottom of the shaft or to any other point within the shaft and stays there for any length of time, the record sheet will pass horizontally across the pen point 133 and a horizontal line will 100 be made. It is to be noted that the record sheet 46 upon which the time record is made is relatively narrow and it is for this reason that I have provided the means illustrated for indirectly transmitting the movement of 105 the slide or cross head 50 to the pen 133 in place of directly connecting the pen to the cross head. The use of the angular armed lever 126 secures a proportionate but relatively small movement of the pen 133 upon 110 each reciprocation of the slide or cross head. It is pointed out that the mechanism for advancing the large gear 26 is so constructed that no matter from which point the cage or car may start back, the pawl carrier is released to return. This is to take care of any irregularity that might take place in the winding of the engine. Of course, there is a limit that must be considered, and the cage or car will have to travel at least twenty-five 115 feet in the shaft before a record of that travel can be made. Of course, as all shafts are far deeper than this, anything less than twenty-five feet will not be worth recording. It will also be noticed that the time record 120 sheet 46 faithfully charts what may be termed the events of each trip of the car—the time it started, where it stopped, how long it stopped, whether it went out again, and when it returned to the starting point. 125 130

Inasmuch as it is difficult to count the trips upon the time record sheet, it is especially convenient that when the trips are made rapidly and in close succession I have provided the mechanism recorder which makes the counting of the trips simple.

While I have heretofore described my recording device as being connected to hoisting machinery, it is equally applicable to the counting of cars passing over a track and is particularly useful for counting mining cars. While the recording mechanism is the same as that previously described, the means for actuating the recording mechanism will 10 of course be different.

Fig. 11 shows my mechanism as attached to a track for recording the passage of cars. In this figure, C designates a rail of an ordinary railway track and 135 designates a 20 movable rail which is so mounted that it normally projects above the face of the rail C and in position to be engaged by the tread of a car wheel. This rail 135 is of a length equal to the wheel base of the car. Disposed 25 opposite to the track is a foundation plate or base 136 which has the upwardly projecting ears 137 between which is mounted the weight lever 138. The long arm of this lever extends outward and is provided with 30 a shifting weight which may be in any desired position upon the arm. Mounted upon the ties which support the rail C and at opposite ends of the rail 135 are the ears 139 and attached to the opposite ends of the rail 35 135 are the levers 140. These are pivoted to the projecting ears 139 and then converge as at 141 and are connected at their converging ends by means of a link 142 to the lever 138 between the fulcrum 137 and the 40 weight. The short arm of the lever is connected by means of a link 143 to a lever 144 fulcrumed upon the upwardly projecting standard 145. The opposite end of the lever 45 144 is pivotally connected to the rod 17 of the recording mechanism, as previously described. The recording mechanism is precisely the same as that previously described except in three particulars. The time actuated recorder is removed and in place of 50 the ratchet toothed rod 71 and the rod 69 only one cam rod is used, as illustrated in Fig. 10, this rod being designated 146. The rod 146 at its lower end is enlarged as at 55 147 and formed with a cam edge 148 which engages with the roller 76 of the pawl carrier 55. The upper portion of the rod 146 is perfectly plain, that is, it is not provided with teeth, and it is clamped rigidly to the face of the cross head 50 so that it moves 60 positively therewith. Inasmuch as the travel of the rod 17 will be the same at all times where the device is used as a car counter, there is no necessity of providing the mechanism previously described whereby only the 65 initial travel of the cross head 50 acts to

shift the pawl carrier. Furthermore, by substituting the rod 146 for the rod 71 the extra jerks due to the momentum of rapidly passing cars are taken care of, as when the gear is once advanced the rod 146 can travel 70 up or down to a considerable distance without communicating any further motion to the advancing gear. The third change above referred to is in the position of the top rolling disk pen or stylus designated 53 75 in Fig. 3.

Where the device is to be used for recording the passage of cars it is not desirable that a line of full length should be recorded upon the recording sheet, and for that reason I change the position of the top stylus roller designated 53 in Fig. 3. As illustrated in Fig. 2, this upper stylus 52 is mounted in a slot 149 and is slideable outward in this slot or chamber within which it is contained. This stylus or roller carrier 52 has a laterally projecting pin 150 projecting out through a slot in the side plate which closes in the side of the projecting end of the stylus carrier 50 as illustrated 80 in Fig. 7. Both sides of the casing within which the stylus 52 are mounted are provided with this slot and if the stylus 52 be reversed, that is, turned upside down, it will be seen that the pin 150 which normally projects out on the left hand side of the carrier 50 will be projected out on the right hand side of the carrier into contact with a vertical guide 151 which is supported 85 in any suitable manner upon the plate 19. This guide has a straight face for a greater portion of its length but is cut away at 152. When in the reciprocation of the carrier 50 the pin 150 reaches this cutaway portion 90 152, it will be forced inward bringing the stylus roller in contact with the recording sheet. Above and below this cutaway part 152, however, the flat inner face of the guide 151 will bear against the pin 150 and will hold the stylus carrier inward with its stylus 95 wheel or roller away from the recording sheet. Thus only a relatively short record mark will be made upon the sheet for each reciprocation of the stylus carrier 50. If it were not for this, the lines would be very 100 irregular owing to difference in momentum of cars passing over the rail 135.

While I have illustrated what I believe to be the best form of my invention, I do not wish to be limited thereto, as it is obvious that many changes may be made in the details of construction and arrangement of parts without departing from the spirit of the invention.

While I have shown my counting and recording mechanism as applied to elevators and as applied to railways, I wish it distinctly understood that it might be used in other situations without changing the principle of its construction.

Having thus described the invention, what I claim is:

1. A counting mechanism including a record sheet holder, a stylus coacting with the holder and means for reciprocating the stylus across the record sheet holder, and means actuated by the reciprocation of the stylus and engaging the record sheet holder for advancing the record sheet holder a predetermined distance only in a direction at right angles to the direction of movement of the stylus upon each complete reciprocation of the stylus.

2. A counting mechanism including a record sheet holder, a fixed stylus, a movable stylus disposed below the fixed stylus, means for reciprocating the stylus across the sheet holder, means actuated by the reciprocation of said means for advancing the record sheet holder one step for each reciprocation of the stylus, and means shifting the second-named stylus into action with the record sheet holder at predetermined intervals.

3. A counting mechanism including a rotatable, cylindrical sheet holder, a stylus carrier reciprocating parallel to the axis of the holder, an upper fixed stylus carried upon the carrier, a lower outwardly shiftable stylus carried thereby, means actuated by the reciprocation of the carrier for advancing the holder one step at each reciprocation of the carrier, and means for causing the projection of the shiftable stylus at predetermined intervals.

4. A counting mechanism including a cylindrical record holder, a ratchet wheel operatively connected with the record holder to rotate the same, a reciprocating stylus carrier movable parallel to the axis of the holder, a stylus thereon coacting with the holder, and means operatively connected with the carrier and operatively engaging the ratchet wheel for advancing the ratchet wheel and record holder one step only upon each complete reciprocation of the carrier.

5. A counting mechanism including a rotatable record holder, a ratchet wheel operatively connected with the record holder to rotate the same, a reciprocating stylus carrier movable parallel to the axis of the record holder, a fixed stylus carried thereon, a movable stylus carried thereon, means operatively engaging the reciprocating stylus carrier and the ratchet wheel whereby the latter may be advanced one step upon each reciprocation of the stylus carrier, and means operatively engaging the movable stylus and operatively engaged by said ratchet wheel for projecting the movable stylus at definite intervals into coaction with the record holder.

6. A counting mechanism including a rotatable record holder, a ratchet wheel operatively engaging the holder to rotate the same, said ratchet wheel being formed on one face with a plurality of radial lugs, a

stylus carrier reciprocatable parallel to the axis of the record holder, a fixed stylus mounted upon the carrier and engaging with the record holder, an outwardly shiftable stylus also mounted upon the carrier, means operatively engaging the stylus carrier and the ratchet wheel whereby the latter may be advanced one step for each reciprocation of the carrier, and means for projecting the movable stylus into engagement with the record holder and including a member disposed in the path of movement of the lugs on the ratchet wheel and periodically engaged by the latter.

7. A counting mechanism including a rotatable record holder, a wheel having peripheral ratchets and operatively engaged with the record holder to rotate the latter, the face of the wheel being provided at definite intervals with radially extending lugs, a stylus carrier reciprocatable parallel to the axis of the holder, means operatively connected with the stylus carrier and with the ratchet wheel whereby the latter may be advanced one step for each reciprocation of the carrier, a fixed stylus mounted upon the carrier and coacting with the record holder, a shiftable stylus mounted upon said carrier and shiftable into and out of coaction with the holder, a member movable in one direction to project the movable stylus, a lever operatively connected to said member to shift the same, and a plunger engaging said lever and disposed in the path of movement of said lugs.

8. A counting mechanism including a cylindrical rotatable record holder having gear teeth at one end, a ratchet wheel, a pinion carried by the ratchet wheel and engaging the gear teeth on the record holder, a stylus carrier reciprocatable parallel to the axis of the record holder, a stylus projecting therefrom and coacting with the holder, guides for the carrier, a pawl carrier movable across the periphery of the ratchet wheel, a pawl carried thereby and engaging the teeth of the ratchet wheel, and a rod having a cam face on one edge and engaging said pawl carrier, said rod being operatively connected to the stylus carrier to reciprocate therewith whereby to reciprocate the pawl carrier and advance the ratchet wheel one step upon each reciprocation of the stylus carrier.

9. A counting mechanism including a rotatable record holder, a rotatable ratchet wheel operatively connected with the record holder to rotate the same, a stylus carrier reciprocatable parallel to the axis of the holder, a stylus carried thereby and coacting with the holder, a pawl carrier disposed adjacent the ratcheted edge of the ratchet wheel, a spring urging the pawl carrier in one direction, a pawl mounted on the carrier and engaging said ratchet teeth, and a rod operatively connected to the stylus carrier and having two

- straight edges joined by an inclined cam edge, said cam edge when the stylus carrier and rod are reciprocated acting to shift the pawl carrier in one or the other direction 5 and the straight edges holding the pawl carrier from movement.
10. A counting mechanism including a movable record carrier, means for moving the record carrier and including a member 10 having ratchet teeth, a frame disposed parallel to the face of the record holder, a stylus carrier guided in said frame and reciprocatable parallel to the face of the record holder, a stylus carried thereby, a pawl carrier supported adjacent to the toothed edge of the ratchet member, means urging the pawl carrier in one direction, a roller mounted on the pawl carrier, and a rod operatively connected at its upper end to the stylus carrier 15 to move therewith, the lower portion of the rod being formed on one edge with a cam face adapted to engage said roller whereby to reciprocate the roller in a direction to advance the ratchet toothed member upon a movement of the rod in one direction and 20 permit the return of the pawl carrying member upon a movement in the other direction.
11. A counting mechanism including a rotatable record holder, a ratchet wheel operatively connected to the roller to rotate the same, the edge of the ratchet wheel being toothed and the face of the wheel being formed with radially disposed uniformly spaced lugs, a stylus carrier reciprocatable 25 parallel to the axis of the record holder, a movable stylus carried thereby, and projectable into coaction with the record holder, means holding the movable stylus out of 30 acting position, a fixed standard passing through the stylus carrier and on which the stylus carrier is shiftable, a rod linked to the standard for movement in an arc parallel thereto, said rod operatively engaging said 35 shiftable stylus, and means disposed in the path of movement of the lugs for reciprocating said rod to thereby project the movable stylus into operative position at definite intervals.
- 40 12. A counting mechanism including a cylindrical rotatable record holder, a ratchet wheel operatively engaging the record holder to rotate the same, a stylus carrier reciprocatable parallel to the axis of the record holder, an outwardly shiftable member 45 slidably mounted in the end of the stylus carrier, a stylus mounted thereon and coacting with the record cylinder, a standard passing through the stylus carrier, a rod also passing loosely through the stylus carrier, parallel links connecting the rod with the standard, a spring drawing the rod in one direction, said rod bearing against the rear end of the stylus carrying member, an 50 arm connected to one end of the rod, a lever 55 engaging at one end with said arm, and a plunger disposed beneath the other end of the lever and having one end disposed in the path of movement of said lugs whereby to reciprocate the plunger and lever at intervals to thereby project the movable stylus 60 at intervals.
13. A counting mechanism including a rotatable record holder, a rotatable ratchet wheel operatively connected with the record holder to rotate the same, a stylus carrier reciprocatable parallel to the axis of the holder, a stylus carried thereby and coacting with the holder, a pawl carrier disposed adjacent the ratcheted edge of the ratchet wheel and movable parallel thereto, means urging the pawl carrier in one direction, a pawl mounted on the carrier and engaging said ratchet wheel, a rod operatively connected to the stylus carrier and having its rear edge formed with an inclined cam face 65 engaging the pawl carrier to shift it in one direction, the forward edge of the rod being formed with downwardly inclined ratchet teeth, a pawl mounted upon the stylus carrier and engageable with said ratchet teeth, and means for releasing the pawl for engagement with the ratchet teeth of the rod after the pawl carrier is moved upward a predetermined extent.
14. A counting mechanism including a rotatable record holder, a ratchet wheel operatively connected with the record holder to rotate the same, a stylus carrier reciprocatable parallel to the axis of the holder, a stylus carried thereby and coacting with the holder, a pawl carrier disposed adjacent the ratcheted edge of the ratchet wheel, means urging the pawl carrier in one direction, a pawl mounted on the carrier and engaging the ratchet teeth, a rod frictionally engaging the stylus carrier, said rod on its rear edge having a cam face engageable with said pawl carrier to shift the same when the rod is raised and on its other face being provided with downwardly inclined ratchet teeth, a pawl mounted upon the stylus carrier and engaging the ratchet teeth of said rod, means operating after a predetermined upward movement of the rod and carrier to release the pawl from the rod, and means for limiting the further upward movement of the rod with the carrier.
15. A counting mechanism including a rotatable record holder, a ratchet wheel operatively connected with the record holder to rotate the same, a stylus carrier reciprocatable parallel to the axis of the holder, a stylus carried thereby, a pawl carrier reciprocatable parallel to the plane of the ratchet wheel, a pawl mounted thereon and engaging the ratchet teeth of the wheel, a release rod frictionally contacting with the face of the stylus carrier, a cam rod frictionally contacting with said release rod, and formed

with stops engaging the upper and lower ends of the release rod, said release rod having an outwardly projecting flange at its lower end and an outwardly projecting 5 stop flange at its upper end, a pawl carried by the stylus carrier having a tooth adapted to engage with the teeth of the cam rod and having a face engageable by the edge of the release rod, a cam engaging with the lower 10 flange of the release rod to urge the release rod outward to thereby engage and release the pawl on the carrier, and a stop limiting the upward movement of both rods.

16. In a mechanism of the character described, a reciprocating member, a cam rod having frictional engagement therewith, said rod having one edge thereof formed with an outwardly inclined cam and the other edge formed with ratchet teeth, a 15 pawl on the reciprocating member engaging said ratchet teeth, a reciprocatable member moving in a plane transverse to the first-named member and reciprocated by the cam edge on the cam rod, means for releasing the 20 pawl from its engagement with the teeth of the cam rod upon a movement of the first-named reciprocating member in one direction and to a predetermined extent, and means for limiting the upward movement of 25 the cam rod with the first-named reciprocatable member whereby to permit the reciprocating member to travel further upward without a corresponding movement of the cam rod.

17. In a mechanism of the character described, a member reciprocatable in one direction, a member reciprocatable at right angles to the first-named member, a rod 30 moving with and actuated by the first-named member and engaging with and actuating the second-named member, means for causing a movement of the rod with the first-named member during the initial movement of the first-named member in one direction, means for releasing the rod from 35 movement with the first-named member after a predetermined common movement whereby to permit the first-named member to move independently of the rod, means for securing a common movement of the rod and first-named member upon the initial 40 portion of the reverse movement of the first-named member, and means for preventing further common movement of the rod with the first-named member after a predetermined 45 common movement has been secured to permit the first-named member to travel the remainder of the distance to its initial position independently of the rod.

18. A counting machine including a rotatable record holder, a rotatable ratchet wheel operatively connected with the record holder to rotate the same, a stylus carrier reciprocable parallel to the axis of the holder, a stylus carried thereby, a pawl carrier dis-

posed adjacent the ratcheted edge of the ratchet wheel, means urging the ratchet wheel in one direction, means mounted on the carrier and engaging the teeth of the ratchet wheel, a cam rod frictionally bearing against the face of the stylus carrier and having a cam face engaging the pawl carrier to operate the same, means for engaging the rod with the stylus carrier for common movement in one direction during 70 the initial portion of said movement, means for releasing said rod from its engagement with the carrier upon a further movement in the same direction to permit the carrier to move independently of the rod, means 75 for again engaging the carrier and the rod upon a reverse movement of the carrier in a reverse direction, and means for preventing the further movement of the rod with the carrier after a predetermined common movement to permit the carrier to move to its initial position independently of the cam rod.

19. In a mechanism of the character described, a reciprocating element, a clock 90 actuated drum rotated in a plane at right angles to the plane of reciprocation of said element, a lever having arms arranged at an acute angle relative to each other, the lever being pivoted at the junction of the 95 arms, a pin carried by the reciprocating element and engaging a slot in one of said arms, a slide having operative engagement with the other of said arms and mounted for reciprocating motion transversely to the face 100 of the drum, and a stylus carried by the slide and coacting with said drum.

20. In a mechanism of the character described, a supporting base, a clock actuated drum mounted upon the base, a record sheet 105 mounted upon the drum and having time subdivisions, guides mounted upon the base, an element reciprocating in said guides, a lever having angularly diverging arms and pivotally mounted at the junction of the 110 arms, a pin carried by the reciprocating element and engaging a slot in one of said arms, a slide movable parallel to the line of movement of said member and operatively engaging with the other of said arms, a resilient support mounted on the slide, and a stylus carried upon the resilient support and coacting with the drum and record thereon.

21. A counting and recording mechanism of the character described including a cylindrical rotatable record holder, a rotatable ratchet wheel operatively connected with the record holder to rotate the same, a stylus reciprocable parallel to the axis of the holder, a stylus carried thereby and coacting with 120 the holder, means actuated by a reciprocation of said stylus carrier for giving a step by step movement to the ratchet wheel, a time actuated drum, a record sheet mounted thereon having time graduations, a stylus co- 125

- acting with the record sheet, and means actuated by the reciprocations of the first-named stylus carrier for shifting the second-named stylus across the record sheet a distance less than but proportionate to the movement of the first-named stylus carrier. 5
22. A counting mechanism including a rotatable record holder, a stylus reciprocatable parallel to the axis of the holder, means for causing a forward movement of the holder a predetermined distance upon each complete reciprocation of the stylus carrier, a stylus mounted on the carrier and coacting with the record holder, a time actuated 10 drum, a record sheet mounted thereon, a stylus coacting with the record sheet, and means actuated by the stylus carrier for reciprocating said last-named stylus across the face of the record sheet a distance less than 15 but corresponding to the length of travel of the first-named stylus carrier. 20
23. A mechanism of the character described including a shiftable record holder, a stylus reciprocating element, a stylus coacting with the reciprocating element and with the record holder, means actuated by and at the beginning of travel only of the reciprocating element in one direction for giving an advancing movement to the record 25 carrier a predetermined distance. 30
24. In a mechanism of the character described, a rotatable record holder, a reciprocating member, an actuating member engaging the reciprocating member and operatively engaged with the record holder to shift the latter upon a movement in one direction, and means for causing a movement of the actuating member with the reciprocating member during the first part of the 35 movement of the reciprocating member in a direction whereby to actuate and advance the record holder a predetermined distance and for causing the movement of the reciprocating member and actuating member in 40 the opposite direction upon the first part of the return movement of the reciprocating member whereby to cause a return of the actuating member to its initial position. 45
25. The combination with a winding mechanism and a car actuated thereby, of a rod operatively connected with the mechanism to be shifted in one direction upon a rotation of the winding mechanism in one direction and in the other direction upon a reversal of the movement of the winding mechanism, mechanism actuated by said rod for recording the number and extent of reciprocations of said rod, and separate time actuated mechanism for recording the time of said reciprocations. 50
26. In a mechanism of the character described, a reciprocating element, a movable record sheet, means for supporting the record sheet, a stylus operatively carried by the reciprocating element and engaging said 55 sheet, means for shifting the record sheet holder a predetermined distance upon each reciprocation of the reciprocating element, a continuously moving clock-actuated record carrier, and a stylus reciprocating over said 60 last-named record carrier and driven by said reciprocating element. 65
27. A counting mechanism including a cylindrical record holder, a reciprocating stylus carrier movable parallel to the axis of the holder, a stylus thereon coacting with the carrier, and means operatively connected with the carrier and operatively engaging said record holder for advancing the record holder one step only upon each complete reciprocation of the carrier. 70
